SUSPENSORY

Charlotte E. Smith, Topeka, Kans.

Application October 18, 1935, Serial No. 45,625

3 Claims. (Cl. 128—159)

This invention relates to surgical appliances in the nature of a suspensor constructed to efficiently support the testicles without the employment of belts, bands or other objectionable parts to engage the body of the wearer, and the primary object of the invention is the provision of such a suspensor and the inclusion in the structure thereof, of unique and novel means for supporting the sack of the suspensor.

This invention has for one of its objects, the provision of a suspensor like that shown in Patent Number 1,288,718, issued to myself and Charles J. R. Smith, on December 24, 1918.

One of the important aims of the present invention is the provision of a suspensor of the aforementioned character, which has as a part thereof, unique and novel apparatus for supporting the sack of the suspensor in operative position with respect to both scrotum and penis, that comprises a strap novelly attached to portions of the suspensor sack and provided with adjusting buckles and fastener to the end that the mouth of the sack may be made larger or smaller to suit requirements and the sack of the suspensor may be raised or lowered with respect to the said fastener as the suspensor is being positioned.

There are a large number of minor objects of this invention which will appear during the course of the following specification, referring to the accompanying drawing, wherein:

Figure 1 is a perspective view of a suspensor embodying this invention and illustrating the same in place upon a garment.

Fig. 2 is a stretch-out view of the blank, which is cut preparatory to forming the sack.

Fig. 3 is an enlarged, side elevation of the suspensor, and,

Fig. 4 is a central section through the same. In constructing the suspensor, the fabric employed for making the main portion thereof should be of some soft material, such as silk cloth, and the blank which is cut therefrom is illustrated in Fig. 2. The portion 6 of the fabric forms sack 8 and the projecting pieces 9 thereof, when folded as shown at the lower portion of Fig. 2, create the two tongues 10 that extend upwardly from sack 8 so that their opposed adjacent edges will form an opening 12. Reinforcement 14 is provided along the lower edge of opening 12 by folding back and stitching the member 16 which is shown in the stretched out condition in Fig. 2.

In forming tongues 10, the material is doubled back over itself along line 18 and then stitched

as indicated at 20. These lines of stitching are arcuate so as to assist in forming a substantially oblong opening 12, and when the material is folded back along line 18, portion 22 of the blank overlies a part of portion 6 thereof so that a double thickness is provided at the zone of connection between tongues 10 and sack 8.

Stitches 24 secure portion 22 in place on the inner face of sack 8, as illustrated in Fig. 4. Edge 26 of the material is gathered as illustrated at 28 so that the side of the sack which is at the back of the scrotum will be drawn in to a contour like that shown in Figs. 3 and 4. This upper edge of sack 8 is provided with a padding 30 which underlies the back portion of the scrotum next to the body and this pad of soft, long napped material prevents objectionable rubbing.

The ends of tongues 10 are secured together by stitching them to a buckle 32 and when the ends are so secured together, opening 12 is presented at one side of sack 8. With the ends of tongues 10 held above the top edge of padding 30, notches or inwardly extending slits 34 are presented which will allow contracting the material at the mouth of sack 8 without objectionable bunching of the fabric.

The novel means for supporting the sack 8 and for adjustably maintaining the mouth of this sack a desired size, is in the form of a strap or straps 36. In the preferred embodiment, this strap 36 is a continuous piece of non-elastic fabric, the ends of which are secured to sack 8 at the upper portion thereof and on each side respectively of tongues 10 and in spaced relation to each other and to said tongues. More specifically, the ends of strap 36 are secured to the sack 8 on each side thereof at the edges of notches 34. In so attaching strap 36, rearwardly and downwardly extending portions 38 thereof are presented.

These portions pass over the top of tongues 10 and when shortened by drawing the doubled strap through buckle 32, the mouth of sack 8 is made smaller. Buckle 32 may be easily and quickly moved to the clamping position and in order to position sack 8 the proper distance from fastener 40, the doubled strap 36 is rebent upon itself so that a slide buckle 42 may be employed to govern the length of strap 36 between buckle 32 and fastener 40.

Fastener 40 is of the conventional type and may be secured to any form of undergarment or even to the outer shirt of the wearer. The zone of attachment should be on the button side of

the garment, as illustrated in Fig. 1, so that when the other side is lapped thereover, fastener 40 will be covered and out of view.

In placing the suspensory, sack 8 is caused to encase the scrotum as the penis extends through opening 12. Fastener 40 is secured to the garment and thereafter buckles 32 and 42 are adjusted to provide for comfortable and proper support, which includes raising or lowering sack 8 with respect to fastener 40 and also the independent adjustment of the size of the top of sack 8. Strap 36 is non-elastic and the entire suspensory may be removed and washed without injury to any parts thereof.

Having thus described the invention, what is claimed as new and desired to be secured by Letters Patent is:

1. A suspensory of the character described comprising an open top sack; a pair of tongues extending upwardly from the top of the sack and having their free ends secured together to form an opening therebetween at the side of said sack; a buckle carried by the free ends of said tongues; and a strap having its ends secured to spaced apart points on the top edge of the sack and extending adjustably through said buckle and upwardly therefrom to present means for fastening the sack in operative position and for selectively increasing or decreasing the size of the mouth of the said sack.

2. A suspensory of the character described comprising an open top sack; a pair of tongues extending upwardly from the top of the sack and having their free ends secured together to form an opening therebetween at the side of said sack; a buckle carried by the free ends of said tongues; and a strap having its ends secured to spaced apart points on the top edge of the sack and extending adjustably through said buckle and upwardly therefrom to present means for fastening the sack in operative position and for selectively increasing or decreasing the size of the mouth of the said sack.

said tongues; and a strap having its ends secured to spaced apart points on the top edge of the sack and extending adjustably through said buckle and upwardly therefrom to present means for fastening the sack in operative position and for selectively increasing or decreasing the size of the mouth of the said sack, said opening at the side of the sack being below said buckle, the points of attachment of the ends of the said strap being on each side respectively of said 10 tongues.

3. A suspensory of the character described comprising an open top sack; a pair of tongues extending upwardly from the top of the sack and having their free ends secured together to form an opening therebetween at the side of said sack; a buckle carried by the free ends of said tongues; a strap folded back upon itself having its ends spaced apart and secured to points at the top of said sack on each side respectively of said 20 tongues and extending through said buckle and therebeyond to provide means for fastening the sack in operative position; a padding on the top of the sack along the length thereof between the ends of the strap; a fastener threaded upon said strap; and another buckle joining the bight of the folded strap and the portion thereof between the first mentioned buckle and said fastener whereby to form a loop to adjustably maintain 30 the fastener a desired distance from the sack, the first mentioned buckle being in sliding engagement with the strap for selectively increasing or decreasing the size of the mouth of the said sack.
